UNITED STATES PATENT OFFICE

2,009,871

SHOE SEWING MACHINE

Albert W. Bradbury, Clifftondale, Mass., assignor
to United Shoe Machinery Corporation, Paterson, N. J., a corporation of New Jersey

Application March 12, 1934, Serial No. 715,110

4 Claims. (Cl. 112—45)

The present invention relates to improvements in wax thread sewing machines of the McKay type, such for instance as described in the patent to Ashworth No. 1,914,936, granted June 20, 1933, 5 having a straight hook needle, a rotary horn and other stitch forming and work feeding devices. More particularly the invention relates to improvements in a McKay type sewing machine adapted to lay a seam beneath a concealed flap 10 formed by making a single continuous cut about the marginal portion of the shoe outsole.

The horn of a McKay machine is of limited size and rotatably mounted so that all of the stitch forming devices, aside from the needle threading 15 means, are mounted to operate at the opposite side of the work from the horn, materially restricting the movements and positions assumed by the stitch forming devices. The work is usually fed by a feed point acting to penetrate a short 20 distance below the surface of the work without passing through, and the presser foot is intermittently raised a uniform distance to release the work for easy movement while being fed, so that the feed point will not tear the surface acted on. 25 The arbitrary addition of other work engaging devices to the already crowded space is, therefore, likely to aggravate those difficulties. For this reason, the use of both a flap turning tool and a channelling knife of a McKay type of sewing machine has, therefore, been considered impractical. 30 Accordingly, before a McKay shoe having a seam concealing flap may be sewed, it is the usual practice to provide an additional groove in which the seam is embodied in the surface of the outsole beneath the flap to permit the flap to be cemented in 35 smooth contact with the surface under the flap after sewing.

The object of the present invention is to provide a novel and improved sewing machine of the 40 McKay type arranged not only to cut a groove, but at the same time to raise the flap of a shoe sole, so that the seam and groove may be formed in accurate alinement simultaneously beneath the flap.

The features of the present invention include the provision, in a McKay type shoe sewing machine having substantially all of the stitch forming devices at one side of the work, of a work 45 grooving knife and a flap turning tool also arranged to engage the side of the work acted upon by the other stitch forming devices. As illustrated, the flap turning tool is yieldingly mounted on the presser foot, so that the pressure of the 50 flap tool against the work may be relieved with-

out actually being disengaged from the work during feeding movements of the feed point.

These and other features consist of certain constructions, combinations and arrangements of parts, the advantages of which will be apparent 5 from the following description.

In the drawings illustrating the invention in its preferred form, Fig. 1 is a view in front elevation of a portion including the stitch forming and work feeding devices of a sewing machine embodying the features of the invention; Fig. 2 is a corresponding view on an enlarged scale of a portion of the mechanism shown in Fig. 1; Fig. 3 is a view in side elevation of the parts shown in Fig. 2 looking from the right; Fig. 4 is a sectional view taken along the line 4—4 of Fig. 2; Fig. 5 is a view in side elevation on a still further enlarged scale of the lower portion of the presser foot and the flap turning tool mounted thereon; and Fig. 6 is a view in front elevation of the parts illustrated 10 in Fig. 5.

The machine illustrated in the drawings comprises a straight hook needle 10, a rotary work supporting horn 12 having a needle threading whirl 14, a rotary shuttle 16, a presser foot 18, a 15 feed point 20, and a loop spreader 22. All of the stitch forming and work manipulating devices enumerated, with the exception of the horn and the whirl, are located to operate from the upper 20 side of the work, indicated at 24.

The presser foot 18 is supported at the end of a vertical reciprocating presser foot bar 26. The presser foot bar is resiliently held in a lowered position and is intermittently retracted to release the work by mechanism indicated generally at 28, 35 which in turn is operated in suitable timed relation with the other stitch forming devices. The feed point 20 is clamped at the lower end of a carrier 30 slidably mounted for vertical movement 40 towards and away from the work in a guide frame 32 which is pivotally mounted at 34 on the frame of the machine. Feeding movements are imparted to the work by oscillating the feed point carrier about the pivot 34 while the presser foot releases the work, the presser foot mechanism 28 45 acting to raise the presser foot a uniform distance from the surface of the work, regardless of the thickness of the work.

In the machine embodying the present invention, both a work grooving knife and a flap turning 50 tool are provided, so that a shoe having a seam concealing flap may be sewed without providing a separately cut groove in which the seam must be formed. The grooving knife, indicated at 35, is pivotally mounted on a horizontal arm 36 secured 55

to the lower end of the presser foot bar 26, and is so arranged on the arm that the lower end of the knife will penetrate the work to the proper depth while the presser foot engages the work. The 5 lower end of the knife passes through an opening formed in an extending portion of the feed point 20 to move the knife 35 in the line of feed with the feed point. The presser foot being raised during the feeding movement of the feed point, 10 no cutting action of the knife 35 will take place, but during the back feeding movement of the feed point, the work is clamped by the presser foot and a groove will be formed by the knife corresponding in length to the distance between stitches. A 15 machine embodying mechanism for so forming a stitch receiving groove in the work is more fully described in the application of Whitaker Serial No. 675,739 filed June 14, 1933.

The flap turning tool, indicated at 38, is mounted 20 directly on the presser foot at one side of the line of feed and in advance of the lower work engaging surface 40 of the presser foot. The flap turning tool operates to engage a surface 42 of the work, beneath a flap portion 44 formed by 25 making a single continuous cut at an angle to the surface of the work around the margin thereof before sewing. The flap 44 is raised from a horizontal position to an upright position illustrated more clearly in Fig. 3, and the lower edge of the 30 tool 38 is bent rearwardly to conform more closely to the curvature of the flap. The position of the flap turning tool 38 at one side of the feed point does not interfere with the operation of the feed point and grooving knife, and since it operates to 35 engage the work in advance of the presser foot it does not interfere with the clamping action of the presser foot against the surface 42.

To permit the flap turning tool to engage the work while the presser foot is raised, the tool is provided with a cylindrical shank portion 48 slideable in a vertical passage formed in the presser foot. To prevent twisting of the flap turning tool, the intermediate portion of the tool is of 40 squared section to engage flat vertical sides of a recess 50 in the presser foot. The upper end of 45 the tool is engaged by a short, flat spring member 52 fastened at one end to the upper surface of the presser foot by a screw 54 and forked at the other end. The forked end of the spring engages 50 slots 56 formed in the cylindrical portion of the flap turning tool to hold the tool in place. The spring 52 also causes the flap turning tool to be forced yieldingly against the surface 42 of the work when the presser foot is down.

55 The invention having been thus described, what is claimed is:

1. A shoe sewing machine of the McKay type

having, in combination, a straight hook needle, a rotary work supporting horn, a presser foot for alternately clamping and releasing the work supported by the horn, a feed point acting on the side of the work engaged by the presser foot to feed the work when released, and other work engaging devices including a tool for raising a seam concealing flap in advance of the stitch forming devices and a channelling knife arranged to form a stitch receiving groove in the surface 10 of the work beneath the flap.

2. A shoe sewing machine of the McKay type having, in combination, a straight hook needle, a rotary work supporting horn, a presser foot for alternately clamping and releasing the work supported by the horn, a feed point acting on the side of the work engaged by the presser foot to feed the work when released, and other work engaging devices including a tool for raising a seam concealing flap in advance of the stitch forming devices and a channelling knife connected to the feed point for reciprocating movement in the line of feed to form a stitch receiving groove in the surface of the work beneath the flap.

3. A shoe sewing machine of the McKay type having, in combination, a straight hook needle, a rotary work supporting horn, a presser foot for alternately clamping and releasing the work supported by the horn, a feed point acting on the side of the work engaged by the presser foot to feed the work when released, and other work engaging devices including a channelling knife arranged to form a stitch receiving groove in the surface of the work and a tool yieldingly mounted on the presser foot for engagement with the work while the presser foot releases the work to raise a seam concealing flap in advance of the engagement of the other stitch forming devices with the work.

4. A shoe sewing machine of the McKay type having, in combination, a straight hook needle, a rotary work supporting horn, a presser foot for alternately clamping and releasing the work supported by the horn, a feed point acting on the side of the work engaged by the presser foot to feed the work when released, and other work engaging devices including a channelling knife connected to the feed point for reciprocating movement in the line of feed and a tool yieldingly mounted on the presser foot for engagement with the work while the presser foot releases the work to raise a seam concealing flap in advance of the engagement of the other stitch forming devices with the work.

ALBERT W. BRADBURY.
